UNITED STATES PATENT OFFICE.

HARRY P. FIELD, OF BERWICK, PENNSYLVANIA, ASSIGNOR TO AMERICAN CAR AND FOUNDRY COMPANY, OF NEW YORK, N. Y., A CORPORATION OF NEW JERSEY.

MINE CAR.

Application filed June 8, 1925. Serial No. 35,639.

In the drawings:

Fig. 1 is a side elevation of a mine car constructed in accordance with this invention, parts being broken away to show the 5 journal box and wheel hood more clearly;

Fig. 2 is a top plan view of the mine car shown in Fig. 1;

Fig. 3 is a partial vertical transverse section of the mine car shown in Fig. 1 taken 10 on the line 3—3 of Fig. 2;

Fig. 4 is a side elevation of a mine car of modified construction, parts being broken away to show the journal box, drawbar and bumper more clearly;

15 Fig. 5 is a top plan view of the mine car shown in Fig. 4;

Fig. 6 is a partial vertical transverse section of the mine car shown in Fig. 4, taken on the line 6—6 of Fig. 5;

20 Fig. 7 is a partial side elevation of another modified construction, parts being broken away to show the wheel hood more clearly;

Fig. 8 is a fragmentary top plan view 25 of the mine car shown in Fig. 7; and

Fig. 9 is a partial vertical transverse section of the mine car shown in Fig. 7.

This invention relates to mine cars and has as an object to provide an improved 30 mine car of composite construction. It is also an object of this invention to provide a mine car of the type specified in which the side floor portions are formed integral with the sills and are corrugated to receive 35 bracing members. It is also an object of this invention to provide an improved bumper for mine cars of the type specified which will facilitate repairs to the car floor. It is also an object of this invention to provide 40 a mine car of improved construction which is rugged and inexpensive to manufacture and readily and cheaply repaired and which is adapted to be readily modified in various details without modification 45 of the main features of the construction.

With these and other objects in view a mine car constructed in accordance with this invention comprises, as shown in the drawings, metal plates 1 forming the side floor 50 portions of the car and having their inner edges bent to form Z-shape sills having vertical webs 2 and inwardly projecting bottom flanges 3, the top flanges of the sills coinciding with and being part of the side

floor portions. The outer edges of the 55 plates 1 are bent upwardly to form reenforcing flanges 4. The sills are supported upon journal boxes 6 which are shaped to fit the sills and have flanges 7 and 8 engaging the bottom and top sill flanges, respectively, to which they are secured by bolts 9 and 10.

Axles 12 carrying wheels 14 are mounted in the journal boxes 6, the wheels extending into openings 15 formed in the plates 1 to receive the wheels and extending to the outer 60 edges of the plates 1, the openings in the plates being covered in the structures shown in Figs. 1 to 6 by wheel hoods 16 formed integral with the plates 1 by pressing portions of the plates upwardly. In the modified construction shown in Figs. 7 to 9, the 65 openings 151 in the plates 1 are formed by cutting away portions of the plate 1, the openings being covered by wheel hoods 161 secured to the side plates 1 by rivets 162 70 and bolts 10. The side plates 1 are also provided with equally spaced corrugations 75 18 which extend inwardly from the flanges 4 and are merged into the plates 1 adjacent the sills. The flanges 4 are continued 80 around the corrugations in each of the structures and in the structures shown in Figs. 1 to 6 the flanges 4 extend about the outer edges of the wheel hoods 16 which extend to and merge into the flange 4.

In the structures shown in Figs. 1 to 3 and 7 to 9, inclusive, wood sides 20 are shown carried by the side floor portions and engaging the flanges 4 while in the modification shown in Figs. 4 to 6 metal sides 201 are shown secured to the flanges 4. In each of the constructions the sides are braced by strap braces 22 extending beneath the car body from the top of one side to the top of the other side. The braces 22 are secured to the wood sides by bolts 23 and to the metal sides by rivets 231. The braces 22 lie in the corrugations 18 and are fastened therein by rivets 24 and are secured to the flanges 4 of the plates 1 by bolts 23 100 or rivets 231 and to the flanges 3 of the sills by the bolts 9.

Extending from end to end of the car is the inverted U-shape drawbar or buffer member 26 having laterally projecting flanges 28 105 secured to the braces 22 by the bolts 34. Between the drawbar 26 and the sills are placed the planks 32 fastened to the strap

braces 22 by bolts 34 and which, with the web 36 of the drawbar 26, form the center floor portion of the car. The drawbar 26 and some planks 32 project beyond the end braces 22 and have secured thereon bumpers 40. The bumpers 40 comprise top plates 42 and bottom plates 44 which extend inwardly as far as the inner edges of the end braces 22 and are secured thereto by the bolts 46 which extend through the upper and lower plates 42 and 44, planks 32 and filler members 48 which are placed between the bottom plates 44 and the bottoms of the planks 32. The top and bottom plates 42 and 44 are joined by face plates 50 which curve slightly from end to end and have horizontal depressions lying on each side of the centers forming anti-climbers, the bottoms of the depressed portions forming surfaces which engage the outer ends of the planks 32. To the web 36 at each end of the drawbar 26 is riveted a drawbar member 52 which has its outer end spaced from the bumper 40 to provide an opening to receive the usual coupling link 25 and is provided with an opening to receive the coupling pin 53 which engages also in alined openings in the bumper 40 and the drawbar 26.

Extending across from sill to sill in line with each brace 22 are ties 60 which rest upon the center floor portion and side floor portions and are secured to the side floor portions by rivets 62 and to the center floor portion by the bolts 34 which secure the planks 32 to the braces 22. At one end the car body is closed by a swinging end gate 66 carried by arms 68 pivotally connected to the car side at 70 and provided with an opening for the drawbar member 52. At its other end the car body is closed by a fixed end 72 secured in place by transverse brace 74 and vertical braces 76.

Secured to the flanges 3 of the sills are brackets 80 in which is pivotally mounted a shaft 81 having crank arms 82 pivotally connected to ends of flexible brake bands 83 which fit over the treads of the wheels and have their opposite ends riveted to brackets 84 secured to the adjacent brace 22. At one end the shaft 81 is provided with a crank arm 85 pivotally connected by a link 86 to a brake lever 87 pivotally mounted in a bracket 88 secured to a side plate 1. The brake lever 87 extends upwardly inside the body of the car through an opening in the side floor 1 and has its upper end bent outwardly and projecting over the side of the car which is slightly lower at this point in order to keep the brake lever from extending above the upper edge of the car side. The brake lever is provided with a projection adapted to engage in the teeth 89 formed on the angle 90 secured to the car side 20 to maintain the brake lever in brake applied position. To 60 protect the brake lever from the lading there

is provided a plate 91 having flanges by which it is secured to a car side, an end and the floor and which forms, with the car side, end and floor, a pocket in which the brake lever operates.

It will be noted that placing the braces 22 in the corrugations 18 provides a clearance beneath the side floor portions at the ends of the car which extends to the bottoms of the side sheets 1 and renders this type of car especially suitable for use with end dumping devices. It will also be noted that in the structures shown in Figs. 1 to 6 extending the wheel hood 16 to the car side, as shown, provides a wheel opening 15 which permits of 75 removing a wheel from its axle without necessitating the removal of the axle from the journal boxes or the removal of the journal boxes from the car body.

It will also be noted that the planks 32 85 adjacent the sills end at the end braces and may be moved longitudinally to remove them from the car upon removal of the bolts which secure them in position. Upon removing the outside planks, the inner planks, when unbolted, may be moved over against the sills and then withdrawn past the bumpers without removing the bumpers from the drawbar member 26. The planks 32 which engage with the bumpers are of the same length so 95 as to engage with the bottoms of the horizontal depressions formed in the bumpers. Planks may be inserted by reversing the operation described above.

What is claimed is:

1. In a mine car, metal side floor portions having their inner edges bent to form sills having vertical webs and inwardly projecting flanges and brace receiving corrugations formed in said side floor portions.
2. In a mine car, metal side floor portions having their inner edges bent to form Z-shape sills and bracing members connecting said side floor portions, said side floor portions having corrugations receiving said 105 bracing members.
3. In a mine car, metal side floor portions having their inner edges bent to form flanged sills and bracing members connecting said side floor portions and engaging 115 flanges of said sills, said side floor portions having corrugations receiving said bracing members.
4. In a mine car, metal side floor portions having their inner edges bent to form sills 120 and their outer edges bent upwardly to engage with the car sides.
5. In a mine car, metal side floor portions having their inner edges bent to form sills, wheel openings formed in said side 125 floor portions and bracing members connecting said side floor portions, said side floor sections having corrugations receiving said bracing members.
6. In a mine car, metal side floor portions 130

- having their inner edges bent to form sills, a center floor portion between said sills, tie members on said center floor portion and connecting said side floor portions, bracing members under said center floor portion and connecting said side floor portions and means connecting said tie and bracing members and center floor portion. 5
7. In a mine car, metal side floor portions having their inner edges bent to form sills and their outer edges flanged, sides secured to said flanges and bracing members secured to said sides, floor portions and sills, said floor portions having corrugations receiving 10 said bracing members.
8. In a mine car, metal side floor portions having their inner edges bent to form flanged sills and their outer edges flanged, sides secured to said flanged outer edges, a floor portion between said sills and bracing members secured to said floor portions, sides and flanges, said side floor portions having corrugations receiving said bracing members. 20
9. In a mine car, metal side floor portions having their inner edges bent to form sills having inwardly projecting flanges, a center floor portion between said sills, tie members connecting said side floor portions, bracing members engaging said sill flanges and means connecting said tie and bracing members and center floor portion, said side floor portions having corrugations receiving said 30 bracing members.
10. In a mine car, sills, a drawbar member, planks between said sills and drawbar member and bumpers carried by said drawbar member and some of said planks, said planks adjacent said sills being removable past said bumpers and providing openings 40 for the removal of said bumper carrying planks.
11. In a mine car, sills, a drawbar member, planks between said sills and drawbar member, some of said planks projecting beyond the other planks, and bumpers carried by said drawbar member and said longer planks, said shorter planks being removable past said bumpers and providing openings for the removal of said longer planks. 45
12. In a mine car, sills, a drawbar member, planks of different lengths between said sills and drawbar member, said shorter planks lying next said sills, and bumpers carried by said drawbar member and said 50
- longer plank, said shorter planks being removable longitudinally of said car past said bumpers providing openings for the removal of said longer planks. 55
13. In a mine car, a central wood floor, combined sills and side floors in part underlying said central wood floor, extending thence upwardly substantially vertically and then outwardly in a plane below the wheel treads, said combined sills and side floors having hooded openings for the wheels and ties connecting said side floor portions above said central floor. 60
14. In a mine car, a buffer member, combined sills and side floor members, wood floor portions overlapping said buffer and combined members and ties connecting said side floor portions above said wood floor. 65
15. In a mine car, journal boxes having supporting faces in a plurality of planes, a central floor portion supported by relatively low supporting faces of said journal boxes, combined sills and side floor members supported upon said relatively low supporting faces and upon other relatively high supporting faces of the journal boxes and ties 70 connecting said side floor portions above said central floor. 75
16. In a mine car, journal boxes, combined sills and side floor members connected directly to and supported upon said journal boxes, a central floor portion intermediate said journal boxes, and ties connecting said side floor portions above said central floor. 80
17. In a mine car, combined sill and side floor members having horizontal flanges, a central floor resting on said flanges, a central buffer member, ties connecting said combined members above said central floor, side walls, and braces secured to the outsides of said side walls connected with said central 90 floor and buffer member. 95
18. In a mine car, metal side floor portions having brace receiving corrugations formed therein. 100
19. In a mine car, a central floor portion, metal side floor portions and means on opposite sides of said floor connecting said side floor portions, said side floor portions having corrugations receiving some of said connecting means. 105

In witness whereof I have hereunto set my hand.

HARRY P. FIELD.
